COMBINED LUNCH KIT AND HANDBAG

Carl W. Sundberg, Birmingham, and Montgomery
Ferar, Huntington Woods, Mich.

Application October 30, 1950, Serial No. 12,776

Term of patent 14 years

(CL. D87—3)

To all whom it may concern:

Be it known that we, Carl W. Sundberg, a citizen of the United States, residing at Birmingham, Oakland County, Michigan, and Montgomery Ferar, a citizen of the United States, residing at Huntington Woods, Oakland County, Michigan, have invented a new, original, and ornamental Design for Combined Lunch Kit and Handbag, of which the following is a specification, reference being had to the accompanying drawings, forming a part thereof, in which

Figure 2 is another perspective view of the combined lunch kit and handbag with the door to the purse compartment and the lunch compartment each being partly open, and with the shoulder strap being disconnected at one end to permit a clearer showing of the interior of the lunch compartment; and

We claim:

The ornamental design for a combined lunch kit and handbag, as shown.

CARL W. SUNDBERG.
MONTGOMERY FERAR.
